Term of patent 14 years

(Cl. D33—7)

FIGURE 1 is a front perspective view of a table desk, showing our new design;

FIGURE 2 is a rear perspective view thereof; and

FIGURE 3 is a fragmentary perspective view of the leg structure.

The dominant features of the design reside in the portions shown in full lines in the drawing and are characterized by legs of angular cross section which are recessed into the side panels and spaced from the adjacent edges of the panel, in combination with the framed panels on the front and rear faces of the pedestals, substantially as shown.

The side of the desk opposite to that shown is similar.

We claim:

The ornamental design for a table desk or similar article, substantially as shown and described.
